US00D776414S

(12) **United States Design Patent** (10) **Patent No.:** **US D776,414 S**
(45) **Date of Patent:** **** Jan. 17, 2017**

(54) **INSOLE**

(71) Applicant: **XiaoLan Qin**, Dongguan (CN)
(72) Inventor: **XiaoLan Qin**, Dongguan (CN)
(73) Assignee: **Dongguan LanHui Commodity Technology Co., Ltd.**, Dongguan (CN)
(**) Term: **14 Years**
(21) Appl. No.: **29/495,290**

(22) Filed: **Jun. 30, 2014**(30) **Foreign Application Priority Data**

Dec. 31, 2013 (CN) 2013 3 0657731
(51) **LOC (10) Cl.** **02-04**
(52) **U.S. Cl.**
USPC **D2/961**
